UNITED STATES PATENT OFFICE.

CHARLES H. HARTMAN, OF LOUISVILLE, KENTUCKY, ASSIGNOR TO WALTER F. STIMPSON, OF LOUISVILLE, KENTUCKY.

KNIFE-EDGE PIVOT FOR SCALES.

Application filed June 19, 1922. Serial No. 569,817.

To all whom it may concern:

Be it known that I, CHARLES H. HARTMAN, a citizen of the United States of America, residing at Louisville, in the county of Jefferson and State of Kentucky, have invented 5 certain new and useful Improvements in Knife-Edge Pivots for Scales, of which the following is a specification, reference being had therein to the accompanying drawings.

The invention relates to the manufacture of knife-edge pivot unit for scales and consists in the novel construction as herein-after set forth.

15 In the drawings:

Figure 1 is a perspective view of the pivot;

Figures 2 and 3 are perspective views of the knife-edge portion and the body portion detached;

20 Figure 4 is a cross-section showing the knife-edge portion and body portion in interlocked engagement; and

Figure 5 is a similar view showing these parts in locked engagement.

25 Figure 6 is a view similar to Fig. 5 showing a modified construction.

In the manufacture of knife-edge pivots one method is to take bar stock and to grind or otherwise fashion the end portions there- 30 of into a V-shape, leaving the central portion of full cross-section. This results in forming at the points of change in cross section lines of weakness. Also, there is consider- 35 able waste of stock due to the cutting away of the ends. With my improved construc- 40 tion I combine a bar of uniform V-shaped cross section with a body of lesser length having a V-shaped channel therein for receiving the central portion of said portion and being secured thereto.

As shown, A is the bar of uniform cross-section throughout its length and B is the body member which, as shown, is of circular cross section and of a length less than that 45 of the bar A. The body portion B has formed therein a V-shaped longitudinally extending channel C adapted to receive the bar A. As shown, the apex of this V-shaped channel is the axis of the cylindrical body

and the outer edge of the bar, when placed in the channel, forms a complementary segment of the cylinder. The bar is then securely attached to the body by any suitable means, which, as specifically shown, consists in chamfering the edges of the bar 50 at D and peening over the adjacent edges of the body as at E. This will produce an effectual mechanical lock and as the bar A is not otherwise attached to the body, there will be no line of weakness, as is the 55 case where the V portions and cylindrical portions are integral. It will be understood that the V-shaped channel is formed of a material of suitable hardness, such as hardened steel, but that the body may be made 60 of relatively soft material.

In the modified construction shown in Fig. 6, the bar A is secured by cutting away either the edge portion of the bar or the body to form a recess, and filling in this re- 70 cess with solder.

What I claim as my invention is:

1. An article of manufacture consisting of a knife-edge bearing unit for scales comprising a bar of uniform V-shaped cross section, a body of a different cross-section and lesser length than the bar engaging the central portion having a V-shaped channel for receiving the central portion of said bar, and means for rigidly locking said bar in 75 said recess.

2. An article of manufacture consisting of a knife-edge pivot unit for scales comprising a bar of uniform V-shaped cross section, a body of cylindrical cross-section 80 and of a length less than that of the bar, being provided with a V-shaped channel for receiving and fitting the cross-section of the bar, and means for rigidly securing said bar in said channel.

3. An article of manufacture consisting of a knife-edge pivot unit for scales comprising a bar of uniform V-shaped cross section, a body of a different cross section and lesser length provided with a V-shaped channel therein for receiving and fitting said bar, a portion of the body at the edge 95 of said channel being deflected to interlock

with said bar and to rigidly retain the same in said channel.

4. An article of manufacture consisting of a knife-edge pivot unit for scales comprising a bar of uniform V-shaped cross-section, and a body of a different cross-section and lesser length of the bar having a V-shaped

channel therein for receiving said bar, the central portion of the outer edge of said bar being chamfered and said body portion being peened over to interlock with said chamfer and to rigidly lock said parts together. 10

In testimony whereof I affix my signature.
CHARLES H. HARTMAN.
